UNITED STATES PATENT OFFICE.

CHAILLIE E. MORGAN, OF ROCKVILLE, INDIANA.

CAN OPENER.

1,415,676.

Specification of Letters Patent. Patented May 9, 1922.

Application filed April 27, 1921. Serial No. 464,847.

To all whom it may concern:

Be it known that I, CHAILLIE E. MORGAN, a citizen of the United States, residing at Rockville, in the county of Parke and State 5 of Indiana, have invented certain new and useful Improvements in Can Openers; and I do hereby declare the following to be a full, clear, and exact description of the invention, such as will enable others skilled 10 in the art to which it appertains to make and use the same.

When utilizing circularly operable openers for cutting the tops of cans, considerable force is required to be exerted to hold the 15 can and prevent its following the cutter.

The present invention combines in a single device means for holding the can and a cutter for severing the top thereof, both the holder and the cutter being adjustable with- 20 in certain limits to different sized cans.

Other objects and advantages will be apparent and suggest themselves as the nature of the invention is understood.

While the drawings illustrate an embodiment 25 of the invention it is to be understood that in adapting the same to meet different conditions and requirements, various changes in the form, proportion and minor details of construction may be resorted to 30 without departing from the nature of the invention.

Referring to the accompanying drawings forming a part of the specification,

Figure 1 is a top plan view of a combined 35 can opener and can holder embodying the invention, and

Figure 2 is a section thereof on the line 2—2 of Figure 1.

Corresponding and like parts are referred 40 to in the following description and designated in the several views of the drawings by like reference characters.

The can holder comprises a clamp and a pair of pivoted members in cooperative relation 45 with the clamp, whereby to contract the same and grip the can to be held. The clamp consists of a band 1 usually of metal and expansible whereby to be contracted and grip the can to be held during the cut-

ting of the top thereof. The pivoted members 2 cross near one end and are pivotally connected at the point of crossing. The long arms of the pivoted members 2 constitute handles, whereas the short arms have opposite ends of the band 1 connected thereto. The band 1 is provided at one end with an eye 3 which engages one of the members 2. A number of hooks 4 are provided at the opposite end of the band 1 and any one of the hooks is adapted to detachably engage the other one of the members 2. The hooks 4 provide convenient means for adjusting the clamp for different sized cans. The hooks 4 may be provided in any manner and face outwardly so as not to interfere with the gripping action of the clamp. When the outer ends of the members 2 are pressed together, the clamp 1 is contracted and grips the can embraced thereby.

A bracket 5 is secured to the clamp 1 and 70 is substantially of V-form, the outer ends of the diverging elements being bent in the same direction substantially at a right angle and riveted or otherwise secured to the band 1. A post 6 is pivotally mounted upon the inner end of the bracket 5 and an arm 7 is pivoted to the upper end of the post 6 and has its outer end offset and provided with a handle 8. A cutter 9 is adjustable on the inner end of the arm 7 and is provided with a cooperating guard 10 to engage the outer side of the can to permit the cutter 9 to be held to the inner wall of the can body with the result that the top is cut close to its outer edge so that the can when opened 80 will admit of the contents being readily removed without danger of marring the same. The cutter 9 is secured in adjusted position upon the arm 7 by a set screw 9a.

The bracket 5 is secured to an end portion 90 of the clamp 1 so as not to interfere with the gripping action thereof. The arm 7 is adapted to be moved at its outer end towards and away from the plane of the cam 1, whereby the cutter 9 may be caused to 95 penetrate the top of the can or moved away therefrom. The arm 7 is also adapted to receive a circular movement with the post 6

as a center so that the cutter 9 may traverse the top of the can and sever the same in a manner well understood.

What is claimed is:

- 5 A device of the character specified comprising a can holder including a clamping band, and pivoted members engaging opposite ends of said band, a bracket secured to an end portion of said band, a post pivotally

mounted upon the inner end of the bracket, 10 and an arm pivoted to the post and provided with a cutter adjustable thereon.

In testimony whereof I affix my signature in presence of two witnesses.

CHAILLIE E. MORGAN.
